United States Patent Office

Des. 201,841
Patented Aug. 3, 1965

201,841

BOTTLE OR SIMILAR ARTICLE

Livingston C. Douglas, Leonia, N.J., assignor to Colgate-Palmolive Company, New York, N.Y., a corporation of Delaware

Filed Mar. 11, 1963, Ser. No. 73,913

Term of patent 14 years

(Cl. D58—9)

FIG. 4

FIG. 5

FIG. 1 is a side elevational view of one side of a bottle embodying my new design, the other side being substantially a mirror image thereof;

FIG. 2 is a front elevational view thereof with the deck hose in a lower position;

FIG. 3 is a rear elevational view thereof;

FIG. 4 is a top plan view thereof; and

FIG. 5 is a bottom view thereof.

The dominant features of my design reside in the portions shown in full lines.

I claim:

The ornamental design for a bottle or similar article, as shown and described.
